94,695

DESIGN FOR A CONDIMENTS HOLDER

Blanchard Osborne Keister, Tazewell, Va.

Application June 15, 1934, Serial No. 52,183

Term of patent 3½ years

To all whom it may concern:

Be it known that I, Blanchard Osborne Keister, a citizen of the United States, residing at Tazewell, in the county of Tazewell and State of Virginia, have invented a new, original, and ornamental Design for a Condiment Holder, of which the following is a specification, reference being had to the accompanying drawing, forming part thereof.

I claim:—

The ornamental design for a condiment holder as shown.

BLANCHARD OSBORNE KEISTER.
